Robert N. Marshall, Maplewood, N. J., assignor to
Bell Telephone Laboratories, Incorporated,
New York, N. Y., a corporation of New York

Application September 9, 1936, Serial No. 64,775

Term of patent 14 years

To all whom it may concern:

Be it known that I, Robert N. Marshall, a citizen of the United States, residing at Maplewood, in the county of Essex and State of New Jersey, have invented a new, original, and ornamental Design for a Telephone Transmitter, of which the following is a specification, reference being had to the accompanying drawing, forming a part thereof.

Fig. 1 is a side elevational view of my new design for a telephone transmitter;

Fig. 2 is another side elevational view;

Fig. 3 is a top plan view; and

Fig. 4 is a perspective view thereof.

I claim:

The ornamental design for a telephone transmitter, as shown.

ROBERT N. MARSHALL.
